DYEING CONE STACKS CONTAINING
SEPARATOR DISCS

John A. Soltis, Spartanburg, S.C., assignor to Deering Milliken Research Corporation, Spartanburg, S.C., a corporation of Delaware

Filed July 30, 1962, Ser. No. 213,536
5 Claims. (Cl. 68—198)

This invention relates to a new type of spacer and support for textile fiber filament or yarn wound cones and more specifically to a spacer suitable for separating perforated dyeing cones in dyeing operations.

Spacers are commonly employed between yarn wound cones which have been built into a stack preparatory to dyeing operations. The spacers, in addition to centering the cones, prevent the base portion of one cone from pressing against the yarn wound tip portion of the adjacent cone. As uneven pressure on the yarn results in uneven dyeing, the use of spacers in stacked cone dyeing operations is essential. The spacers of the prior art have been designed, however, in a manner such that one face is suitable for engaging the base portion alone of a cone while the opposite face is suitable for engaging the tip portion alone. In the rapid stacking of yarn wound cones employing the spacer of the prior art, the wrong face of the spacer is frequently presented to the cone thereby producing a nonaligned and unstable stack.

It is therefore an object of this invention to provide a separator disc either face of which will engage the tip portion or the base portion of a truncated yarn dyeing cone.

Another object of this invention is to provide a yarn dyeing means employing a separator disc either face of which will engage the tip portion or the base portion of a truncated yarn dyeing cone.

In accordance with this invention, a spacer has been discovered either face of which is suitable for engaging the tip portion or the base portion of a truncated yarn wound cone. The separator disc comprises an annular ring having beveled edges and having inwardly and outwardly extending annular flange members, said flange members being positioned intermediate the faces of said ring perpendicular to the axis of said ring. The flange portions are preferably of a length equal to the thickness of the walls of the truncated cone which said flange portions are designed to engage. The spacer, which may be made of any material having dimensional stability, is preferably made of organic polymeric plastic having dimensional stability at temperatures of at least about 100° C. and preferably about 150° C. In fabricating the article of this invention, the plastic material may be either reinforced or nonreinforced plastic. Organic polymeric plastic materials which have been found to be especially suitable for purposes of this invention are materials such as for instance polyethylene (high molecular weight), polypropylene, polyformal, polycarbonate, polyurethane, Delrin (polyacetal thermoplastic resin manufactured by E. I. du Pont de Nemours & Company) and the like.

A better understanding of the invention may be had from a description of the drawings in which:

FIGURE 1 is a plan view of the spacer of this invention. FIGURE 2 is a sectional side view of the spacer taken along the plane II—II of FIGURE 1. FIGURE 3 is a sectional side view of a reinforced spacer having a plan view similar to FIGURE 1. FIGURE 4 is a broken diagrammatical view partly in section showing a yarn dyeing installation in which the spacers of this invention are employed and FIGURE 5 is a broken diagrammatical view partly in section showing a yarn dyeing installation in which the spacers of this invention are employed.

2

In FIGURE 1, a plan view of the separator disc is shown comprising a ring 1 having beveled edges 2 and inwardly and outwardly extending annular flange members 3.

5 In FIGURE 2, a cross-sectional side view of the spacer is shown comprising an annular ring 1 having beveled edges 2 and inwardly and outwardly extending annular flange members 3. The flange members 3 are positioned intermediate the faces of the ring 1 perpendicular to the axis of the ring 1. The beveled edges 2 of the ring 1 form an oblique angle with the flange members 3.

In FIGURE 3, a cross-sectional side view of a spacer having a plan view similar to FIGURE 1 is shown comprising an annular ring 4 having beveled edges 6, an annular reinforcing member 7 is interiorly disposed within said ring 4 and inwardly and outwardly extending annular flange members 5. The flange members 5 are positioned intermediate the faces of the ring 4 perpendicular to the axis of the ring 4. The beveled edges 6 of the ring 20 4 form an oblique angle with the flange members 5.

In FIGURE 4, a broken sectional diagrammatical view of a column of truncated yarn wound cones spaced by the members shown in FIGURES 1 and 2 and strung on perforated tubes ready for fluid dye treatment is shown.

25 Referring to the drawing of FIGURE 4, yarn packages 13 on perforated dyeing cones 12 are separated and centered by spacer units 11. The spacer unit 11 will engage either the tip portion of the perforated truncated cone 12 or the base portion of the perforated truncated cone 12 regardless of which face of the spacer 11 is presented to the cone. The spacer separated yarn packages are supported by and strung on the perforated tube 14. The yarn packages 13 are secured in place by means of retainer 15 held down by a wingnut 16 threaded onto the top portion of the perforated tube 14. The stacked yarn package and perforated tube assembly are retained within a chamber 17 having a loading hatch 18. A low pressure seal is maintained between the base of the chamber 17 and the base of the lowermost perforated truncated cone. This 30 low pressure seal is retained throughout the stack by means of a firm juncture between the base and the tip portions of the perforated truncated cones 12 and the spacer devices 11. The topmost low pressure seal is effected by the retainer member 15 and the topmost perforated truncated cone. Pressure from the wingnut 16 provides a sufficient contact between the previously reticulated members to retain the low pressure seal. Dyeing material from a tank 19 is then pumped into the chamber 17 by means of a pump 20. The dyeing material is forced through the perforations of the perforated spindle 14 and then through the perforations in the cones 12 and through the yarn packages themselves.

35 In loading the chamber 17 of FIGURE 4, the perforated spindles 14 and 14' are preferably loaded in a manner such that on each spindle the adjacent truncated cones are aligned tip to tip and base to base. An alignment of this type is possible with spacer devices 11 and 11' in that spacer devices 11 and 11' have identical faces either face of the spacer being capable of receiving either a truncated cone tip portion or a truncated cone base portion. When the truncated cones 12 and 12' are stacked base to base and tip to tip, the initial cones placed on their respective perforated spindles 14 and 14' are deposited in opposite directions, that is to say, truncated cone 12 deposited on spindle 14 is deposited base first 40 while cone 12' mounted on spindle 14' is deposited tip first. The advantage of the deposition of truncated cones in this fashion is that a greater amount of space within the chamber 17 is saved. The space which is saved may be beneficially employed by winding thicker yarn packages 13 and 13' on sleeves 12 and 12' respectively.

45 FIGURE 5 is a broken diagrammatical view partly in

section of a column of yarn wound cones spaced by the members shown in FIGURES 1 and 2 and strung on a perforated tube 24. Truncated cones 22 supporting a yarn package 23 are aligned tip to base, the cones being spaced and secured by spacer member 21. Truncated cones stacked in the manner shown in FIGURE 5 require more space than cones stacked as illustrated in FIGURE 4. It should be understood that although two systematic systems of stacking have been set forth, that the spacer of this invention may also be used to stack cones in a random fashion.

The plastic spacer of this invention may be prepared by any of the fabricating methods common to the plastic art such as for instance injection molding, flash molding, compression molding and the like. When the plastic spacer of this invention is fabricated from organic polymeric plastics alone, however, the thickness of any portion of the spacer is preferably not less than $\frac{1}{8}$ inch. When plastic spacers having areas of less than $\frac{1}{8}$ inch in thickness are prepared, it is found that the spacers lack dimensional stability, that is to say, the pressure from the stacked cones will warp the spacers and thereby prevent the formation of a firm seal between the cones which is necessary for efficient dyeing operations. For maximum space utilization in the dyeing chamber, it is desirable that the spacer be as thin as possible. Where ultra-thin spacers are required, they may be prepared by fabricating the plastic spacer around an annular reinforcing member such as a metal or fiber glass ring. An ultra-thin reinforced spacer of this type is shown in FIGURE 3. The reinforced plastic spacers may be fabricated with areas of about $\frac{1}{16}$ of an inch in thickness, the ultra-thin spacer still having sufficient dimensional stability to effect a seal between adjacent truncated cones.

Having thus described my invention, what I claim is:

1. Dyeing cone stacks comprising truncated dyeing cones and separator means for mounting said cones either narrow end to narrow end, broad end to broad end, or

broad end to narrow end, said separator means comprising an annular ring having beveled edges and having inwardly and outwardly extending annular flange members, said flange members being positioned intermediate the faces of said ring perpendicular to the axis of said ring, said flange members being of a length substantially equal to the thickness of the walls of said truncated cones.

2. The product of claim 1 wherein said separator means is made of an organic polymeric material having dimensional stability at temperatures of 100° C.

3. The product of claim 1 wherein said separator means is made of a high molecular weight polyacetal.

4. The product of claim 1 wherein said separator means has an annular reinforcing member interiorly disposed within said ring.

5. The product of claim 1 wherein said separator means has an annular reinforcing member interiorly disposed within said ring and wherein said flange members have a thickness of about $\frac{1}{16}$ of an inch.
